A. H. HAAG

RADIOCABINET

Filed Oct. 21, 1925

UNITED STATES PATENT OFFICE.

ALFRED H. HAAG, OF BALTIMORE, MARYLAND, ASSIGNOR OF FORTY ONE-HUNDREDTHS TO EMMOR ROBERTS, OF MOORESTOWN, NEW JERSEY, AND OF TWENTY ONE-HUNDREDTHS TO E. HAYWARD FAIRBANKS, OF MERCHANTVILLE, NEW JERSEY.

RADIOCABINET.

Application filed October 21, 1925. Serial No. 63,814.

To all whom it may concern:

Be it known that I, ALFRED H. HAAG, a citizen of the United States, residing at Baltimore, in the county of Baltimore City and State of Maryland, have invented a new and useful Radiocabinet, of which the following is a specification.

My invention consists of a novel construction of a radio cabinet, wherein I made provision for supporting and assembling a radio cabinet together with its loud speaker and batteries, all within a single compact structure, and wherein I provide means for positioning the radio cabinet, so that it is prevented from rearward or sidewise shifting and I also position the loud speaker so that the exit end of the latter overhangs the top of the radio cabinet while the latter overhangs the base of the loud speaker, whereby an exceedingly compact cabinet of a minimum depth is produced.

It further consists of a novel arrangement of the radio supporting shelf and the loud speaker supporting shelf, whereby I am enabled to set the grill for the loud speaker exit as far back as possible and am also enabled to have the exit of the loud speaker overhang the radio cabinet, so that all the space within the cabinet is utilized to a maximum extent.

It further consists of a horizontally disposed alcove located at about the mid height of the cabinet and provided with a drop door and a novel provision of side filler strips having their inner edges of a contour to accommodate the upper and lower mouldings of the radio cabinet, so that a very finished appearance is given to the front of the device when the drop door is open.

It further consists of other novel features of advantage and construction, all as will be hereinafter set forth and pointed out in the claims.

For the purpose of illustrating my invention I have shown in the accompanying drawings several forms thereof which are at present preferred by me, since the same have been found in practice to give satisfactory and reliable results, although it is to be understood that the various instrumentalities of which my invention consists can be variously arranged and organized and that my invention is not limited to the pre-

cise arrangement and organization of the instrumentalities as herein shown and described.

Fig. 1 represents a front elevation of a radio cabinet, embodying my invention.

Fig. 2 represents a vertical section on line 2—2, Figure 1.

Fig. 3 represents a perspective view of one of the filler strips in detached position.

Similar numerals of reference indicate corresponding parts.

In carrying out my invention, I employ a cabinet 1, having the bottom 2, the sides 3, the radio supporting shelf 4, having the rear strip or abutment 5, which fixes the rear position of the radio cabinet 6. The front end of the radio shelf or partition 4 is supported on the top of the front cabinet wall 7, while the ends of said partition are secured to the cabinet sides 3. Above the shelf 4 is the alcove like transverse radio receiving compartment 8, whose top is formed by the horizontal wall 9, against the front edge of which abuts the top of the drop door 10, whose lower edge is hinged at 11 to the front of the shelf 4. At the rear of the top wall 9, and extending above it is the vertical grill 12 in the rear of which is the silk or the like 13. 14 designates a rear loud speaker supporting shelf, which is below the shelf 4

upon which the base 15 of the loud speaker 16 is supported, it being noted that the rear of the shelf 4 overhangs the front of the shelf 14, so that the radio cabinet 6 is permitted to be pushed well into the cabinet, so that the exit end 17 of the horn or loud speaker not only overhangs the radio, but is positioned directly at the rear of the grill 12. As the top and bottom of the radio cabinets are usually provided with top and bottom mouldings as 18 and 19, in order to accommodate the same and to prevent side-

wise movement of the cabinet, I provide the side filler strips 20 and 21 which are constructed as seen in Figure 3. These side strips 20 and 21 are alike except that one of the strips as 21, has a hole 22 therein for the passage of the wires. Each of the strips has the wall 23, which contacts with the inner surface of the contiguous side 3, while the bottom 24 contacts with the top of the shelf 4, and the edge 27 contacts with or is in close proximity to the side of the cabinet

6. The upper and lower grooves 25 and 26 accommodate the upper and lower mouldings 18 and 19 and when the cabinet is in the position seen in Figure 2 it is prevented 5 from rearward or sidewise shifting, as is evident. The front portion of the back of the cabinet is stiffened and reinforced by the vertical transverse rear partition 28 and it will be apparent from the foregoing that 10 the depth of the upper front portion of the cabinet, that is to say, the space between the grill 12 and the partition 28 is but a little greater than the distance between the front exit end 17 of the loud speaker 16 and the 15 base 15 thereof.

It will be further apparent by extending the shelf 4 rearwardly nearly to the juxtaposed wall of the loud speaker 16, I produce an exceedingly compact structure and one 20 having a minimum depth, which is very desirable when the cabinet is to be installed in a small room or in an apartment. It will thus be seen that the rear end of the radio cabinet 6 overhangs the base 15 of the loud 25 speaker and the forward exit end of the loud speaker overhangs the radio cabinet 6 as will be understood from the Fig. 2. The distance between the side walls or panels 3 and the length of the horizontal shelf 4 can 30 be varied according to requirements in order to suit radio cabinets of different lengths. The drop door 10 when in the position seen in Fig. 1 and in dotted lines in Fig. 2 is adapted to be utilized as a writing desk if 35 desired, and when closed keeps the cabinet free from dust and dirt. The lower compartment 29 can be utilized as a receptacle for the A and B batteries 30^x and 31 shown in dotted lines in Fig. 2, so that all the 40 radio elements are compactly, conveniently and effectively housed within a single, ornamental and attractive structure. The space between the top wall 9 and the bottom shelf 4 and the sides 3 forms an alcove which is of 45 just sufficient height to enable the cabinet 6 to be slid into its rearmost position as seen in Fig. 2. The drop door 10 when closed can stand inclined as shown, or it can stand substantially vertical. The brackets 30, 50 which hold the drop door in horizontal position, may be of any suitable construction. It will be understood that the transverse radio receiving compartment 8 is located so that the radio controls are accessible to a 55 sitting operator, and the exit end 17 of the loud speaker and the grill 12 are about on a level with the ears of the sitting operator, so that all the parts are collocated, so as to be readily accessible to the sitting operator, 60 when tuning in the radio.

By my novel construction, the batteries, loud speaker, radio cabinet and the wiring are all contained in a compact and ornamental cabinet wherein the overall dimensions of height and width are reduced to a

minimum, thus rendering the cabinet especially adaptable to small rooms and apartments, where space is to be economized.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention what I claim as new and desire to secure by Letters Patent, is:—

1. In a radio cabinet of the character stated, a horizontally disposed radio supporting shelf extending rearwardly from the cabinet front, a horizontal loud speaker shelf located at a lower level than said first mentioned shelf and extending forwardly so that the rear end of said radio shelf overhangs the front of said loud speaker shelf, and a vertically disposed grill positioned in the upper front portion of the cabinet about on a line with the middle of said radio supporting shelf, whereby when the radio cabinet and loud speaker are assembled, the rear end of the radio cabinet overhangs the base of the loud speaker and the front exit end of the loud speaker overhangs the top of the radio cabinet. 100

2. In a radio cabinet of the character stated, a radio compartment arranged above a horizontally disposed radio supporting shelf extending rearwardly from the front of the cabinet and provided with a stop at its rear to position the radio cabinet, a horizontal loud speaker shelf below the radio supporting shelf and extending forwardly so that the rear end of the radio shelf overhangs the front of the loud speaker shelf, a vertically disposed grill positioned in the upper front portion of the cabinet about on a line with the middle of the radio supporting shelf, whereby when the radio cabinet and loud speaker are assembled the rear end of the radio cabinet overhangs the base of the loud speaker and the front exit end of the loud speaker overhangs the top of the radio cabinet, and vertical filler strips secured to the inner surface of the cabinet side walls. 110

3. In a radio cabinet of the character stated, a radio compartment arranged above a horizontally disposed radio supporting shelf extending rearwardly from the front of the cabinet and provided with a stop at its rear, a horizontal loud speaker shelf 125

below said radio supporting shelf and extending forwardly so that the rear end of the radio shelf overhangs the front of the loud speaker shelf, a vertically disposed grill positioned in the upper front portion of the cabinet about on a line with the middle of the radio supporting shelf, whereby when the radio cabinet and loud speaker are assembled the rear end of the radio cabinet overhangs the base of the loud speaker and the front exit end of the loud speaker overhangs the top of the radio cabinet, a horizontal top projecting wall parallel to the radio supporting shelf whereby an alcove 15 is formed between the cabinet sides, said top wall and said radio cabinet supporting wall and a drop door hinged at its lower end to the front of the radio supporting shelf and having its upper end when closed 20 adapted to abut against the upper wall of said alcove.

4. In a radio cabinet of the character stated, a horizontally disposed radio supporting shelf extending rearwardly from the cabinet front, a horizontal loud speaker supporting shelf located in the rear of said cabinet and at a lower level than said first 25

mentioned shelf and a vertically disposed grill positioned in the upper front portion of the cabinet about on the vertical median line of said radio supporting shelf, whereby when the radio cabinet and loud speaker are assembled, the front exit end of the loud speaker overhangs the top of the radio cabinet. 35

5. In a radio cabinet of the character stated, a horizontally disposed radio supporting shelf extending rearwardly from the cabinet front at substantially the height of a sitting operator, a horizontal loud speaker shelf located in the rear of said cabinet, a vertically disposed grill positioned in the upper front portion of the cabinet about on the vertical median line of said radio supporting shelf, whereby when the radio cabinet and loud speaker are assembled, the front exit end of the loud speaker overhangs the top of the radio cabinet, and a drop door hinged at its edge on the front of said radio supporting shelf and adapted 40 to stand horizontal when open, and to conceal the radio when closed. 45 50

ALFRED H. HAAG.
